CLAIM

The ornamental design for a hair color applicator, as shown and described.

DESCRIPTION

FIG. 1 is a front, left side, top perspective view of a hair color applicator showing our new design;
FIG. 2 is a front elevational view thereof;
FIG. 3 is a rear elevational view thereof;
FIG. 4 is a left side view thereof;
FIG. 5 is a right side view thereof;
FIG. 6 is a top plan view thereof;
FIG. 7 is a bottom plan view thereof;
FIG. 8 is a cross-sectional view thereof, taken in the direction of line 8-8 of FIG. 4; and,
FIG. 9 is a reference perspective view of the embodiment thereof, indicating a rotating direction by arrows.

The portions depicted by broken lines are for illustrative purpose only and form no part of the claimed design.

The long and short dashed lines illustrate a boundary of claimed design and unclaimed ones.
